PNEUMATIC DISPATCH CARRIER

James G. Maclare, San Francisco, Calif.

Application December 9, 1931, Serial No. 579,865

12 Claims. (Cl. 243—34)

This invention relates to pneumatic dispatch carriers, and more particularly to carriers of the take-apart type suitable for department store pneumatic dispatch tube systems.

5 Take-apart carriers have shells that are easily separable without the use of tools or a work bench.

The carrier air disk now in general use is described in the U. S. Patent No. 808,263 dated January 2, 1906. This older disk is clamped between the closed end of an outer carrier shell and the face of a felt buffer head by means of two screws that are riveted after tightening to insure a permanent fastening.

15 To renew the air disk, the screws are sawed through and discarded, and this operation requires that the carriers be collected and taken to a work bench.

These air disks are generally made of thin 20 flexible material and slightly larger than the transit tube. They are an important part of the carrier, materially increasing the carrier speed when in flight. The disks are practically a necessity when the tube system is equipped with power 25 saving valves of the dual flow type that function by reason of the tube being obstructed by a carrier.

The take-apart carrier now in general use is described in the U. S. Patent No. 1,553,869 dated 30 September 15, 1925, and a dual flow power saving valve is described in the U. S. Patent No. 1,637,314 dated January 26, 1927.

As the carrier air disks wear out faster than the felt buffers, it will contribute to the satisfactory operation of the pneumatic tube system, and encourage the care-taker to keep carriers in good repair, if worn air disks can be quickly and economically replaced.

35 My invention accomplishes this purpose. It also provides for the use of thinner, and therefore cheaper carrier buffers, a gauge for indicating when a carrier buffer is worn out, and provides means to lengthen a standard carrier for operation with a sorter which deflects carriers in one direction or another, according to the carrier length. A form of this type of sorter is described in U. S. Patent No. 1,383,194 dated June 28, 1921.

40 A preferred form of the invention is shown in the drawing, in which:

Fig. 1 is a side view of a carrier equipped with my air disk and a new arrangement of buffer assembly.

45 Fig. 2 shows the front end of a carrier equipped

with my disk and a form of buffer now in general use.

Fig. 3 is a plan view of my air disk or packing ring.

Fig. 4 is a plan view of a sheet of thin metal cut 5 into a suitable form for a disk holder.

Fig. 5 is a disk holder side view after the form in Fig. 4 has been cupped.

Fig. 6 is a longitudinal sectional view through the center of the carrier and drawn to large scale. 10 It shows the assembly illustrated in Figs. 2 and 7.

Fig. 7 is an end view of the carriers shown in Figs. 1 and 2.

In Fig. 2 is shown a felt buffer head 1 such as is now standard in the trade. They are $\frac{3}{4}$ inch 15 thick and the end 2 is beveled to easily ride over tube joints, etc., and the surface 3 is the sliding surface and subject to wear from contact with the walls of tubing, bends and terminals.

The edge 4 is undercut to provide a space into 20 which the disk 5 may fold when the carrier is in flight. This disk 5 I make in the form of a ring, as shown in Fig. 3. In the preferred form it is made of flexible material and has eighteen pierced slots 6 to fit over the prongs 7 of the 25 holder 8 in Fig. 5. This holder 8 is cupped from the form 9 in Fig. 4. The diameter 10 of the holder 8 I prefer to make equal to the minimum suitable operating diameter of the felt buffer, as an urge to the care taker to replace the felt buffer 30 when it has worn to this diameter.

In Fig. 1 I show a thinner felt buffer 11 having the same amount of wearing surface 3 as in Fig. 2. The thickness of felt required for the undercut space 4 is omitted and instead a spacing disk 12 35 of any hard suitable material such as leather or fibre and of suitable diameter, is clamped between the air disk 5 and the buffer 11. This provides a recess 13 for the air disk to fold into. The disk 12 can be of considerable thickness when it is desired to make up a carrier of longer overall length 40 from stock parts, for use with sorting devices.

Obviously, for lengthening purposes, one or more spacing disks can be similarly secured at the opposite end 14 of the carrier, between the 45 closed end of the outer shell 15 and the buffer 16.

These spacing disks are preferably made to closely fit inside the prongs 7 of the holder 8 and larger than the opening 19 in the disk 5.

In Fig. 6, 15 is the outer shell and 17 the inner 50 shell of a take-apart carrier, and it will be understood that in this type of carrier, the shells may be easily separated.

By making the inner diameter 18 of the form 9, a sliding fit over the inner shell 17, and the 55

inner diameter 19 of the air disk 5 sufficiently large to permit its being stretched over the inner shell 17, the disk 5 and the holder 8 can be slipped into place and secured by the open end 5 of the outer shell 15 when the shells 15 and 17 are assembled.

It is possible to omit the holder 8, make the ring of leather and harden the inner edge around the hole 19 of the disk or ring 5, with wax to 10 make it stiff and nonelastic at the center, but left flexible around the outer edge.

Also, a ring can be used for the air disk 5 made from stiff leather or packing. In this case the outside diameter would be a sliding fit in 15 the transit tube. However, the flexible disk secured by a metal holder is the preferred form.

In Fig. 6, 20 is a closure secured to the end of the inner shell 17. 21 and 22 are fillers to equal 20 the thickness of the air disk 5 and the holder 8 and are secured between the buffer head 1 and the closure 20 by means of two screws 23.

It will be noted that whereas in the older form of carrier the air disk is on the closed end of the outer shell, in my drawing it is placed next to 25 the open end of the outer shell and this end of the shell used to secure the air disk in place.

It is to be understood that while preferred embodiments of this invention have been shown herein by way of example, various changes in 30 the proportions and arrangement of parts may be made if desired and that equivalent parts may be substituted for those shown and described herein and that some parts may be omitted without departing from the invention.

35 I claim:

1. In a pneumatic tube carrier having a shell with a buffer secured thereto, a flexible packing ring slidable over the shell separate from the buffer and unattached thereto, and means supported on the carrier shell having prongs extending through and holding said packing ring in operable position against the buffer.

2. In a pneumatic tube carrier having a body with a buffer attached thereto, an air disk abutting the said buffer and held thereagainst, and means separate from any buffer attaching means for securing the said air disk in operable position said means having prongs extending through the disk.

50 3. In a pneumatic tube carrier having a body with a buffer attached thereto, an air disk adjacent to the said buffer and held thereagainst, and means encircling the carrier shell for securing the disk to the carrier, removable without detaching the buffer and having prongs extending through the said air disk.

4. In a pneumatic tube carrier having a body equipped with a buffer head, a packing ring slidable over the carrier body, a holding means 60 loosely encircling the carrier body and engaging the packing ring, and an outer shell securing the packing ring and its holding means in operable position against the buffer.

5. In a pneumatic tube carrier having a body 65 equipped with a buffer head, an air disk having a center opening formed to fit over the carrier

body, a holder for the disk separate from the carrier body, the said holder anchored to the disk near the periphery of the disk center opening, and means removably attached to the body and securing the disk and holder against the 5 buffer head.

6. In a pneumatic tube take-apart carrier having separable inner and outer shells, each shell having one open and one covered end, a buffer head attached to the covered end of each shell, 10 an air disk and holder for same slidable over the inner shell when the shells are separated and secured in operable position by the outer shell when the shells are assembled.

7. In a pneumatic tube carrier of take-apart 15 type having separable telescoping shells, each shell having a buffer head attached to one end thereof, an air disk and holding means for same slidable over the inner shell, said air disk clamped in operable position between a buffer head and 20 the outer shell or a part thereof.

8. In a pneumatic tube carrier of take-apart type having separable telescoping shells, each shell having a buffer head attached to one end thereof, an air disk supported on prongs projecting from an air disk holder, both the disk and holder slidable over the inner shell, said air disk and holder clamped in position between a buffer head and the outer shell or a part thereof.

30 9. In a pneumatic tube carrier of take-apart type having separable telescoping shells, each shell having a buffer head attached to one end, a spacer member between a buffer head and a shell; an air disk slidable over the inner shell, 35 supported by stiffening means and clamped in operable position between a buffer head and the outer carrier shell or a part thereof.

10. In a pneumatic tube carrier of take-apart type having separable telescoping shells, each 40 shell having a buffer head attached to one end thereof, a spacer member between the inner carrier shell and the buffer head attached thereto, and a detachable air disk supported on prongs projecting from an air disk holder, both the air 45 disk and holder slidable over the inner shell, and clamped in position between a buffer head and the outer carrier shell or a part thereof.

11. In a pneumatic tube carrier having a hollow shell with a buffer attached thereto, a packing 50 ring encircling the said shell, means made a part of the ring and independent of the said shell or buffer for stiffening the inner periphery of the packing ring, and means holding the packing ring in operable position.

12. In a pneumatic tube carrier having a hollow shell with a buffer attached thereto, a flexible packing ring having an opening permitting said ring to slide over the said shell, means attached to the ring adjacent the periphery of the 60 opening and holding the ring in conformation with the form of said shell, and a separable outer shell slidable over and attached to said hollow shell and securing the packing ring in operable position against the buffer.

65 JAMES G. MACLAREN.
